UNITED STATES PATENT OFFICE.

EMIL BEHRINGER AND HERMAN BEHRINGER, OF BROOKLYN, NEW YORK.

RADIATOR.

962,189.

Specification of Letters Patent. Patented June 21, 1910.

Application filed August 7, 1909. Serial No. 511,713.

To all whom it may concern:

Be it known that we, EMIL BEHRINGER and HERMAN BEHRINGER, citizens of the United States, and residents of the borough 5 of Brooklyn, in the county of Kings and State of New York, have invented certain new and useful Improvements in Radiators, of which the following is a specification.

Our invention relates particularly to 10 radiators for automobile engines, and the chief object thereof is to devise an improved mode of construction whereby it will become optional to have either a successive or a simultaneous flow of water through the several cooling elements usually comprised in 15 apparatus of this character.

A further object is to provide a structure 20 that will permit the removal of any one of the cooling elements without disturbing the adjustment of the others, nor losing the water contained in the radiator.

Further objects and advantages of the invention will be perceived as the various details thereof are being explained.

25 Referring to the accompanying drawings for a detailed explanation of our invention,—Figure 1 is a front elevation showing it substantially complete, with a portion of the same in section, and some of the cooling 30 elements omitted. Fig. 2 is a right-hand end view of Fig. 1. Fig. 3 is a partial top plan view partly in section. Fig. 4 is a partial section on the line 4—4 of Fig. 1. Fig. 5 is a fragmentary front elevation on an enlarged 35 scale. Fig. 6 is a fragmentary bottom plan, corresponding to Fig. 5. Fig. 7 is a fragmentary rear elevation. Fig. 8 is an enlargement of the upper portion of Fig. 4. Fig. 9 is a fragmentary sectional view of a 40 modification in the structure of the cooling elements; and Fig. 10 is an enlargement of the lower portion of Fig. 4.

The main parts of our improved radiator 45 consist of an upper water-tank 15, a lower 50 water recipient 16, two series of water-compartments 17 and 18 respectively located one under the said tank and the other above the said recipient, and a number of cooling elements 19 connecting the said series of compartments one with the other. The tank is supported from the recipient by means of channel-irons 20, which also surround the ends of the intermediate compartments. No 55 other framework is necessary for the radiator. The tank 15 has a capped orifice 21, through which the radiator can be filled,

and it is further provided with an inlet 22 for the water from the jacket of the engine with which the radiator is connected. Besides these two openings for the inflowing 60 water, the tank has a row of apertures 23 in its bottom, to let the water out and down into the compartments thereunder, in either one of the two ways hereinafter described. One aperture 23 is provided for each compartment 17. An overflow pipe 24 leads the surplus water out of the tank, when it expands under the influence of heat. The two series of compartments 17 and 18 are similarly constructed, excepting that the dividing partitions 25 that separate the compartments from one another do not align in the same vertical planes in the lower series as they do in the upper series, but are staggered or arranged in alternate vertical 70 planes. This arrangement makes it convenient to connect the several compartments of the two series together, through the cooling elements 19, to obtain a continuous flow of water up and down successively. The cooling 75 elements are connected with each compartment in pairs for this purpose, except the first compartment of the upper series and the last compartment of the lower series, which constitute the terminals of the water-course extending between the tank 15 above and the recipient 16 below.

The pairing of the cooling elements 19 and their positions relative to the staggered partitions 25 are represented in the middle 80 portion of Fig. 1, wherein it is seen that the element marked A. on the left is adapted to bring water from an upper compartment B. down into a lower compartment C., while the next element D. will lead the water from 85 the same lower compartment C. up into another upper compartment E., and so on with the other cooling elements 19 and water-compartments 17 and 18. From the compartments 18 the water can reach the recipient 16 through apertures 26, in either one of two ways, as hereinafter described. The said recipient is further provided with an outlet 27, through which the cooled water 90 returns to the engine, and also with a drain 100 28. The latter is suitably stopped at the outer end, as indicated in the lower left-hand corner of Fig. 1.

Slide-valves 29 and 29^a are provided for all the apertures 23 and 26, which apertures 110 remain covered normally, save one of each series, as, contrary to the usual practice, it

is not intended ordinarily in our improved radiator to allow the water to flow directly from the tank 15 into every cooling element 19 thereunder. We do not intend under ordinary conditions, to let the water from the tank 15 flow down simultaneously through every aperture 23 into the upper series of compartments 17, which would cause a direct flow through all the cooling elements 19 at the same time. Our invention admits of such a direct flow, if desired, but we prefer the successive flow from one cooling element to another, and that is why the said two series of compartments 17 and 18 have been provided. With the said compartments the water from the tank can be directed successively through the intermediate cooling elements and thence into the lower recipient 16, simply by leaving two apertures uncovered among the series 23 and 26, which uncovered apertures, as shown in Fig. 1 may be located one at the left end of the tank and the other at the right end of the recipient. To provide for the uncovering of the two apertures last named, while the other apertures may remain covered, we make the valves 29^a of less width than the valves 29, and attach them to the same sidebar 30. It is understood that one sidebar 30, with valves 29 and 29^a, is provided for each one of the series of apertures 23 and 26, and that by manipulating the sidebar to suit, in each instance, the said apertures can either be all covered, or all uncovered, or those having valves of less width can be uncovered while those having the larger valves will remain covered. Each sidebar is designed to pass through guides 31, and the latter carry leaf-springs 32 that bear on the sidebar, to keep the said valves firmly seated. Each row or series of valves 29 and 29^a is slid back and forth, to either cover or uncover, or partly uncover the corresponding row or series of apertures 23 or 26, by means of a head 33, a link 34, and a crank-arm 35. The head 33 is secured to a rounded outwardly-projecting portion 36 of the bar 30, and the link 34 is pivotally attached to both the said head and the crank-arm 35, which also is pivoted at 37 on the rear side of the tank 15. The sidebar 30 passes through a ferrule 38 in said tank, and the movement thereof either way is limited when the crank-arm becomes parallel therewith. The latter acts as a toggle, in conjunction with the link 34, and maintains the bar 30, with the valves 29 and 29^a in their assigned positions, either on or off their respective apertures. A tight joint is effected, with the ferrule 38 by suitable packing provided at 39 on the head 33, and at 40 on the round portion 36 of the bar 30, next to a collar 41 fastened thereon. The packing, as shown, presses against one end

or the other of the ferrule as the bar is drawn in or out. Stops 42 and 43 are provided respectively on the rear of the tank 15 and the recipient 16 as well as on the link 34, to limit the swing of the crank-arm 70 in both its inward and outward movements.

The cooling elements hereinbefore referred to include each a pair of mated passages of wavy outline forming together a line of rhomboids, designated by the number 19. This rhomboidal form of passages is of known construction and therefore need not be minutely shown, nor further described herein, except to say that the meeting ends 44 and 45 of the said passages are connected 80 respectively to tubes 46 and 47, which establish the requisite communication between the said cooling elements and the two series of compartments 17 and 18. In order to establish the said communication, the tubes 46 85 and 47 are all extended at one end beyond the intervening rhomboids so they can pass through openings 48 in the face of each series of compartments. The tube ends that enter the orifices 48 may either be tapered, 90 as shown in Figs. 4, 8 and 10, or they may be straight, as represented in Fig. 9. If tapered, the ends of the tubes are conveniently fitted with a ground joint each in a similarly tapering flanged orifice 49. If straight, the 95 tube ends are preferably provided each with an external flange 50, which is brought to bear against a gasket or washer 51, on the face of the respective compartment. In either case, the inner ends of the tubes entering the compartments are made to engage each a retaining guide 52 therein, and they are laterally apertured, as at 52'. The outer ends of the several tubes 46, 47 are stopped by plugs or heads 53 sweated in the tubes, 100 Bearing on the said outer ends of the tubes 46, 47, are cup-headed set-screws 54, which coact with the said retaining guides 52 in maintaining the said tubes and other parts 105 of the cooling elements 19 in stable positions. The said set-screws are preferably disposed in four lines and staggered, as shown, two lines being provided for the tubes 46, and two lines for the tubes 47, which tubes 46 and 47 are correspondingly disposed. The 110 four lines of set-screws are carried by hinged flaps 55 and 56, two lines on each flap. This arrangement admits of the set-screws being applied to and removed from the outer ends of the tubes simultaneously, at either top or bottom of the cooling elements, once they have been individually adjusted. The several set-screws are applied to their respective heads 53, by forcing their points into cavities 57 provided therefor in said heads. The upper flap 55 is connected to the lower front edge of the tank 15 by a line of hinges 58, and the lower flap 56 is similarly connected by a line of hinges 59, with the outer end of a flanged plate 60 that is secured to and pro- 115 120 125 30

jects forwardly from the face wall of the recipient 16. After they have been adjusted, the set-screws 54 are locked together in their respective lines, and thereby prevented from turning, by means of rods 61, one locking rod being provided for each line of set screws. The rod passes through opposite notches 62 that are cut across the heads of the screws in each line, a sufficient number of notches being made to allow for individual adjustment of each screw. Each rod is held at the ends in a pair of supports 63 and clamped in position by nuts 64 having each an eccentric portion which upon being turned downward operates to lock the respective end of the rods. The said flaps 55 and 56, with the set-screws 54 carried thereby, are caused to bear the outer ends of the tubes 46 and 47, by means of studs 65 and bolts 66. The bolts 66 are pivotally attached to brackets 67 riveted to the channel-irons 20, while the studs 65 are secured to strips 68 riveted respectively on the back of the tank 15 and compartments 17, and on the back of the recipient 16 and compartments 18. Both the studs and bolts enter notches 69 provided in the opposite edges of the flaps 55, 56 and nuts 70 on the ends of both bear against the outer faces of the said flaps when it is desired to keep the latter, with the set-screws thereof, in engagement with the tubular members of the cooling elements. The bolts 66 may be swung on their supports in and out of their notches, in the opposite flaps as shown in Fig. 2, whereas the studs 65, which are passed through the rhomboids of one of the cooling elements, enter and leave their respective notches on straight lines. It will be observed, however, that in neither case is it necessary to unscrew the nuts 70 completely off the ends of their respective studs and bolts to loosen the flaps and allow them to swing open or shut, as may be required.

45 It has already been explained how the water can be caused to flow successively through the cooling elements 19, by leaving only two of the apertures 23 and 26 open; that is, one aperture 23 leading from the tank 15 into one of the upper compartments 17, and one aperture 26 leading from one of the lower compartments 18 into the recipient 16. Manifestly then the water must pass alternately through each one of the upper 50 and lower compartments, and alternately up and down the intermediate cooling elements, before it can reach the recipient 16 from the tank 15. On the other hand, it is likewise evident that by leaving all of the apertures 23 and 26 open, the water will flow from the tank directly into every upper compartment 17, thence down through the cooling elements simultaneously into every lower compartment 18, and from the latter directly again into the recipient 16. All flow is ar-

rested by shutting the two lines of valves 29 and 29^a, when it becomes an easy matter to remove any of the cooling elements for repair, or for any other reason, without losing or spilling an appreciable volume of water 70 from the compartments with which the element is or was connected.

Having described our invention, what we desire to secure by Letters Patent and claim, is:—

75

1. A frameless radiator comprising a water-tank, a water recipient below the same, a series of compartments under said tank adapted to communicate therewith, a second series of compartments on the said recipient 80 adapted to discharge therein, a plurality of cooling elements intermediate said two series of compartments, and supports separating the said water-tank from the said recipient.

2. A radiator comprising a tank, a series 85 of compartments thereunder, one of said compartments being adapted to receive the water from said tank through a suitable aperture, a lower series of compartments including one similarly apertured, a recipient receiving the water from the apertured compartment in said lower series, and cooling elements conveying the water up and down alternately to and from the several upper and lower compartments.

95

3. A radiator comprising a tank provided with discharge apertures, a series of compartments adapted to receive the water each from one of said apertures, cooling elements connected up with said compartments and 100 conveying the water downwardly therefrom, a second series of apertured compartments connected with the lower ends of said cooling elements and receiving the water from the latter, and a lower recipient adapted to 105 receive the water flowing through said other series of apertured compartments simultaneously.

4. A radiator comprising a tank having a 110 suitable number of discharge apertures and valves therefor, a series of compartments adapted to receive the water each from one of said apertures, cooling elements conveying the water flowing out of said compartments, a second series of compartments receiving the water from said cooling elements, a recipient thereunder, said second series of compartments being also provided with apertures adapted to discharge into 115 said recipient and with valves for the latter, and means of controlling said two series of valves whereby one or more can be opened in each series to produce either a successive or a simultaneous flow of the water from the tank to the recipient through the intervening compartments and thereto connected cooling elements.

120

5. A radiator comprising a plurality of compartments, a cooling element therebetween having tubular members, said mem- 125

130

- bers entering said compartments through suitable orifices in one wall thereof, and retaining guides for said members on the opposite wall of said compartments.
6. A radiator comprising a plurality of compartments, a cooling element, tubular members for said elements entering the compartments, guiding means for the inner ends of said members in said compartments, set-screws engaging the outer ends of said members, and movable means for carrying said set-screws and holding them in position to bear on the cooling element.
7. A radiator comprising a series of compartments, cooling elements detachably connected therewith, means for retaining said elements in their operative positions relatively to said compartments, a flap carrying said retaining means and other means for removably holding said flap against said cooling elements.
8. A radiator comprising a series of compartments, cooling elements detachably connected therewith, a flap adapted to cover the connected ends of said elements, cup-headed set-screws carried by said flap and arranged to bear upon said ends of the cooling elements thereunder, a rod passing through opposite notches in the heads of said set-screws to lock them together, and eccentrically operated nuts locking the ends of said rods.
9. A radiator comprising a suitable receptacle with discharge apertures, valves for said apertures, a slidebar controlling said valves, and means for operating said slidebar, including a head thereon, a pivoted crank-arm, and a curved link pivotally attached to both said head and said crank-arm.
10. A radiator comprising a suitable re-
- ceptacle with discharge apertures, valves for said apertures, a slidebar controlling said valves, a ferrule extending through one side of said receptacle and through which a portion of said slidebar is adapted to pass, packing on said portion adapted to bear alternately on the opposite ends of said ferrule, a head secured to the outer end of said slidebar, a link pivotally attached to said head, and a pivoted crank-arm similarly attached to said link.
11. A radiator comprising a plurality of compartments, suitably tapered flanged orifices in the said compartments, tubular members having correspondingly tapered laterally apertured ends passing through the said orifices and cooling elements connecting the said tubular members to conduct the water through the said tubular members from one set of compartments to a second set of compartments.
12. A radiator comprising a plurality of compartments, a cooling element having a tubular member at each end fitted in a suitable orifice in an opposite compartment and projecting inwardly through the same, the inwardly projecting portion of said tubular member being laterally apertured, and a retaining guide in said compartment engaging the inner end of said tubular member.

Signed at the borough of Brooklyn in the 70 county of Kings and State of New York this fifth, day of August A. D. 1909.
